CLAIM

The ornamental design for the embodiments of a sound system, as shown and described.

DESCRIPTION

FIGS. 1-8 are directed to an embodiment of a soundbar for the sound system.

FIG. 1 is a top perspective view thereof;

FIG. 2 is a top and right perspective view thereof;

FIG. 3 is a front perspective view thereof;

FIG. 4 is a right perspective view thereof;

FIG. 5 is a left perspective view thereof;

FIG. 6 is a bottom and left side perspective view thereof;

FIG. 7 is a left side perspective view thereof; and

FIG. 8 is a bottom perspective view thereof.

FIGS. 9-16 are directed to an embodiment of a subwoofer of the sound system.

FIG. 9 is a bottom perspective view thereof;

FIG. 10 is a top and right perspective view thereof;

FIG. 11 is a bottom and left perspective view thereof;

FIG. 12 is a front perspective view thereof;

FIG. 13 is a right perspective view thereof;

FIG. 14 is a left perspective view thereof;

FIG. 15 is a bottom and left side perspective view thereof;

FIGS. 16-23 are directed to an embodiment of a surround speaker of the sound system.

FIG. 16 is a bottom and right perspective view thereof;

FIG. 17 is a front perspective view thereof;

FIG. 18 is a top perspective view thereof;

FIG. 19 is a bottom perspective view thereof;

FIG. 20 is a back perspective view thereof;

FIG. 21 is a left perspective view thereof;

FIG. 22 is a right perspective view thereof; and,

FIG. 23 is a top and left side perspective view thereof.
